1

The present invention relates to absorption refrigeration systems and more particularly to improvements in vapor liquid-lifts utilizing expelled refrigerant vapor for lifting absorption solution for gravity flow through the solution circuit.

Such vapor liquid-lifts have been commonly used in absorption refrigeration systems but all such lifts have a straight cylindrical tube. With a "bubble" type lift, vapor bubbles are introduced into liquid at the base of a cylindrical lift-tube of relatively small diameter to reduce the density of the mixture which rises in a continuous liquid phase in the tube. This type of lift operates well at high pressures but does not operate satisfactorily at low pressures. More specifically, the bubble type lift is not suitable for use in vacuum type absorption refrigeration systems when the liquid being lifted is at a temperature near its boiling point as the liquid flashes into vapor as it rises in the lift-tube. When the liquid being lifted is at a temperature below that at which it flashes, the vapor contacting the cooler liquid condenses. In either case, due to the tremendous volume of vapor relative to liquid per unit of weight in a vacuum type system, the lifting of liquid is erratic and uncontrollable.

Also, when a lift tube larger than one-half inch in diameter is used, the vapor bubbles flow upwardly through the lift-tube without carrying much liquid with them. Therefore when the desired rate of circulation of liquid exceeds the capacity of a single lift-tube, it is necessary to use multiple tubes which increases the cost of the apparatus and introduce another factor which may result in erratic and uncontrolled circulation of liquid.

With a "climbing film" type of lift, vapor is expelled from solution in a cylindrical tube of relatively small diameter, usually heated throughout its length, and the expelled vapor flows upwardly through the center of the tube at high velocity. The drag of the high velocity vapor on the solution produces a rising film of solution on the wall of the lift-tube. This type of lift operates well at low pressure but an individual tube has a limited capacity and also requires a relatively high hydrostatic reaction head. The limited capacity is due to the fact that the periphery of the tube on which the film is lifted varies as the first power of the radius of the tube while its cross-sectional area which controls the vapor velocity varies as the square of the radius. Therefore, only one tube size will

produce a particular relative circulation of vapor and liquid and when a greater capacity is desired than can be produced by a single tube, a plurality of tubes must be provided.

When such a climbing film tube is heated the problem is further aggravated by the unequal variation in the peripheral heating surface and vapor velocity with changes in the radius of the tube. In other words, the tube requires a fixed heat transfer surface to transmit the amount of heat necessary to generate vapor at a rate correlated with a cross-sectional area to produce the required velocity. As the periphery of the tube is the heat controlling factor, which increases as the first power of increments of increase in radius, and the cross-sectional area is the velocity controlling factor, which increases as the square of increments of increase in radius, there is only one optimum tube diameter which will give the heat transfer surface and cross-sectional area required to produce an optimum climbing film action. Such a tube is of relatively small diameter, one-half inch inside diameter for a tube sixty inches long used in a vacuum type absorption refrigeration system using a water solution of 50% lithium bromide by weight when heated by steam at atmospheric pressure, so that two or more lift-tubes must be used when the desired circulation rate exceeds the capacity of a single tube.

Also in the climbing film type of lift, the pressure drop in the lift tube consists of the force of gravity acting on the annular column of solution constituting the climbing film, inertia of the liquid in the film and the frictional drag of the climbing film on the wall of the tube which is equal to and opposes the frictional drag of the vapor on the climbing film. The height of the hydrostatic head of liquid required to balance these forces is a considerable part of the total height of the lift-tube and in practice constitutes nearly one-third of the total height.

With a "droplet" type lift as described and claimed in an application for United States Letters Patent of Norton E. Berry, Serial No. 164,059 filed May 25, 1950, a boiler is provided having a sufficient heating surface to expel refrigerant vapor at a predetermined fixed rate and a cylindrical lift tube extending upwardly from the boiler. The cross-sectional area of the lift tube is correlated to the rate of vapor generation to cause vapor to flow upwardly therethrough in continuous vapor phase at sufficient velocity to lift small droplets of liquid at a controlled re-

2

producible rate at any given capacity. Such a droplet type lift constitutes a considerable improvement in vacuum type absorption refrigeration systems over the "bubble" and "climbing film" types of lifts previously used as it produces a controlled liquid circulation and reduces the height of the hydrostatic reaction head required and the overall height of the apparatus besides providing a simpler construction having a single tube instead of a plurality of tubes which reduces the cost of manufacture and the possibility of leaks.

One of the objects of the present invention is to provide an improved vapor liquid-lift construction which reduces the pressure drop along the tube and the height of the reaction head required to balance the liquid lifting forces.

Another object of the present invention is to provide an improved vapor liquid-lift of the type indicated having a single conduit with a throat for producing the required initial velocity and a progressively divergent passageway above the throat.

Another object is to provide a combined generator and vapor liquid-lift having a single conduit adapted to be heated throughout its length and so formed as to provide both the necessary cross-sectional area and heating surface to lift liquid at any particular capacity.

Still another object is to provide a vapor liquid-lift of the type indicated which operates at a relatively low solution temperature to lift liquid at a uniform rate and one which requires a relatively small heat transfer surface to expel the required volume of vapor.

These and other objects will become more apparent from the following description and drawings in which like reference characters denote like parts throughout the several views. It is to be expressly understood, however, that the drawings are for the purpose of illustration only and not a definition of the limits of the invention, reference being had for this purpose to the appended claims. In the drawings:

Fig. 1 is a diagrammatic view of an absorption refrigeration system incorporating a tapered vapor liquid-lift conduit to provide the divergent passage;

Fig. 2 is a sectional side elevational view of a vapor liquid-lift of modified construction and having a divergent passage formed by progressively flattening the opposite sides of a cylindrical tube;

Fig. 12 is a transverse sectional view taken on line 12—12 of Fig. 9 showing the contour at the bottom of the conduit.

Referring to Fig. 1 of the drawings, the present invention is shown applied to a vacuum type absorption refrigeration system of the type described and claimed in United States Letters Patent to Albert R. Thomas et al. No. 2,282,503 issued May 12, 1942, and utilizing water as a refrigerant and a salt solution as an absorbent. Such a system comprises generally a generator 14, a vapor liquid lift 15, a separating chamber 16, a condenser 17, an evaporator 18, an absorber 19 and liquid heat exchanger 20 interconnected for the circulation of refrigerant and absorbent.

Generator 14 is of novel construction comprising a rectangular vessel having tube sheets 14a at each end and a rounded top 14b, see Fig. 2. Two horizontal rows of tubes 21 extend between the tube sheets 14a with the upper row inclined 35 toward the left and the lower row inclined toward the right as viewed in Fig. 1. A header 22 overlies a tube sheet 14a and encloses the right hand ends of the upper top row of tubes 21 and the header is connected by a conduit 23 to a source of heating medium such as steam. A header 24 overlying the opposite tube sheet 14a encloses the ends of the upper and lower rows of tubes 21. A header 25 below header 22 encloses the outlet end of the lower row of tubes 21. Thus, steam supplied through conduit 23 flows from header 22 through the upper row of tubes and then back into the header 25. Condensate flows from the upper inclined row of tubes 21 into header 24 and condensate flows from the lower inclined row of tubes into the header 25. The lower end of header 24 is connected to header 25 by a pipe 26 and condensate from both headers is drained through a waste pipe 27. Preferably, steam is supplied at atmospheric pressure to the header 22 and is maintained at atmospheric pressure by a vent opening 28 in the header 25. With steam at atmospheric pressure heat will be transferred to the solution in the generator vessel 14 at a predetermined fixed rate corresponding to the area of the heat transfer surface of the tubes 21 and sides of the tube sheets 14a enclosed by the headers 22, 24 and 25. The lower end of the vapor liquid-lift 15, later to be described in detail, projects into the generator vessel 14 for a short distance below the top thereof as shown in Fig. 1 and the liquid-lift utilizes the vapor expelled in the generator vessel to lift solution to the separating chamber 16.

The separating chamber 16 surrounds the upper end of the vapor liquid-lift 15 and has a conical deflecting baffle 29 overlying the upper end of the lift and a plurality of other baffles 30 for separating liquid entrained in the vapor. The top of the separating chamber 16 is connected to the condenser 17 by a conduit 31 and the out-

let from the condenser is connected to the top of evaporator 18 by a conduit 32 having a device 33 therein permitting the flow of liquid refrigerant and non-condensable gases while maintaining a difference in pressure as described and claimed in a copending application of Norton E. Berry, Serial No. 725,000 filed January 29, 1947.

The evaporator 18 comprises a plurality of horizontally arranged tubes 34 having their opposite ends projecting into laterally spaced headers 35 and 36. Conduit 32 from condenser 17 extends into one end of the uppermost evaporator tube 34 in header 35. The end of the next lower tube 34 projecting into header 36 has a cup 37 underlying the end of the uppermost tube to receive liquid refrigerant flowing therefrom and direct it for flow through said next lower tube. Each of the tubes 34 has a cup 37 at one end underlying the end of the tube above to cause the liquid refrigerant to flow successively through each tube from the top to the bottom of the evaporator. Between the headers 35 and 36 the tubes 34 are provided with spaced heat transfer fins 38.

The lower ends of the headers 35 and 36 overlie openings 39 in the top of the absorber 19. The absorber 19 is in the form of a cylindrical shell having a plurality of vertically arranged serpentine coils 40 and a liquid distributing means 41 therein. The liquid distributing means 41 uniformly distributes absorption liquid over the top of the coils 40 which drips from each horizontal coil section 40a onto the next lowermost coil section from the top to the bottom of the coils. Cooling water is supplied to the interior of the coils 40 from any suitable source of supply through a pipe 42 and header 43. Cooling water from the upper ends of the coil sections 40 is delivered through a header 44 and conduit 45 to the condenser 17 and water from the condenser is discharged through conduit 46. Thus, the same cooling water is used to cool the absorber 19 and the condenser 17.

Absorption solution flows by gravity from the separating chamber 16 through the absorption solution circuit back to the generator 14. Absorption solution weak in refrigerant flows from the separating chamber 16 to the liquid distributor 41 in a path of flow comprising conduit 49, inner passages 50 of the liquid heat exchanger 20 and conduit 51 connected to the liquid distributor. Absorption solution strong in refrigerant flows from the absorber 19 to the generator 14 in a path of flow comprising conduit 52, outer passages 53 of the liquid heat exchanger 20, leveling vessel 54 and conduit 55 to the base of the generator. Liquid heat exchanger 20 is arranged with its passages 50 and 53 arranged generally horizontal to take advantage of the decrease in height of the apparatus resulting from the improved lift-tube construction 15, as later explained, but is inclined at a slight angle to the horizontal to prevent the accumulation of vapor or gas bubbles on the heat transfer surfaces. Leveling vessel 54 has a relatively large volume so that variations in liquid flow in the solution circuit will have a negligible effect on the liquid level x in the vessel during operation of the system.

A purging device 56 is connected to the absorber 19 by a suction pipe 57 and has a cooling coil 58 connected between cooling water conduits 42 and 45 and a fall tube 59 depending therefrom. The purging device 56 is connected to conduit 51 to receive a portion of the absorption

solution weak in refrigerant flowing toward the absorber 19 which flows over coil 58 to produce a relative vacuum for withdrawing non-condensable gases from the absorbent and deliver them through the fall tube 59. The bottom of the fall tube 59 is connected to a riser 60 connected at its lower end to conduit 52 and having a storage vessel 61 at the upper end. With such a construction non-condensable gases are withdrawn from the system and delivered to the storage vessel 61 while the absorption solution is delivered to the conduit 52 flowing toward the generator vessel 14.

A concentration control of the type described and claimed in United States Letters Patent to Lowell McNeely 2,485,904 issued March 29, 1949 is provided for storing liquid refrigerant in accordance with the difference in pressure between the high and low pressure sides of the system. 15 The concentration control comprises a vessel 62 having a conduit 63 connected to receive refrigerant overflowing from the lowermost tube of the evaporator 18, a vent tube 64 connecting the top of the vessel to header 35, and a conduit 65 20 connecting the bottom of the vessel to the generator vessel 14.

The generator 14 and condenser 17 operate at a subatmospheric pressure corresponding to the vapor pressure of the refrigerant at its condensing 25 temperature, for example, one pound per square inch absolute, and the evaporator 18 and absorber 19 operate at a lower pressure corresponding to the vapor pressure of the refrigerant in the absorbent, for example, one-tenth of a pound per 30 square inch absolute. The pressure difference is maintained between the condenser and evaporator by the device 33 and between the generator and absorber by liquid columns in conduits 51 and 52. To this end, the liquid heat exchanger 20 is 35 located below the absorber 19 and solution will stand at a level x in leveling chamber 54 only a few inches above the bottom of the vapor liquid-lift 15, at a level y in conduit 49 connected to conduit 51 through liquid heat exchanger 20 and at a level z in conduit 52.

In accordance with the present invention the vapor liquid-lift 15 comprises an upright conduit having a restricting throat a and a progressively increasing cross-sectional area above the throat. The cross-sectional area of the throat a is correlated to the rate of vapor generation in the generator 14 to cause vapor to flow upwardly 40 through the conduit in continuous vapor phase at sufficient velocity to lift droplets of liquid at the desired rate. The individual droplets of liquid are lifted by the frictional drag of the vapor on their surface and the throat area a is of a size to produce an initial vapor velocity and upward force on a number of droplets corresponding to the amount of liquid to be raised sufficient to overbalance their inertia and the force of gravity to impart momentum to the droplets. The area b at the upper end of the diverging portion is of a size to produce a velocity and upward force on the droplets just sufficient to 45 overbalance the force of gravity. Actually in certain lift conduit constructions the velocity at area b may be slightly less than that required to balance the force of gravity due to the residual momentum of the droplets. Thus, the cross-sectional area of the lift conduit 15 gradually increases from the area a to the area b to produce a varying velocity sufficient to lift liquid at the desired rate with a minimum pressure drop 50 through the conduit.

In the embodiment of the invention illustrated in Fig. 1 the vapor liquid-lift conduit 15 is in the form of a tapered tube having the required cross-sectional area a at the bottom and cross-sectional area b at the top and progressively diverging from the bottom to the top. The lower end of the tube 15 projects into the top of the generator vessel 14 and the upper end of the tube projects through the bottom of the separating chamber 16. For any particular capacity the surface of the tubes 21 and tube sheets 14a underlying the headers 22, 24 and 25 is designed to provide the heat transfer surface required to expel the amount of vapor for that capacity. With steam at atmospheric pressure and temperature and a fixed heat transfer surface, the rate of heat transfer will be constant for a given generator pressure. A tapered lift-tube 15 is then selected having cross-sectional areas a and b of the largest size to produce stable operation at the lowest heat input and highest condenser pressure to be encountered. Such a vapor liquid-lift will operate with a minimum pressure drop in the conduit. When operating with a minimum pressure drop, the rate of liquid circulation may be controlled by a restricting orifice 55a in conduit 55. For example, with a vacuum type absorption refrigeration system of 20 tons ice-melting capacity per 24 hours, utilizing a 50% water solution of lithium bromide by weight and heated by steam at atmospheric pressure, a lift-tube 56 inches long having a cross-sectional area or throat a of 9.8 square inches and a cross-sectional area b of 26.5 square inches produces a controlled relative circulation of 4 pounds of vapor to 64 pounds of solution per minute with a 2-inch difference in height h between the liquid level x in leveling chamber 54 and the bottom of the lift-tube 15. A refrigeration system of 5 tons ice-melting capacity operating under similar conditions with a lift-tube 45 inches long having a cross-sectional area a of 1.7 square inches and a cross-sectional area b of 4.4 square inches will produce a controlled relative circulation of 1 to 16 with a difference in height h at both full and half heat input capacity. One form of the invention having now been described in detail, the mode of operation of the complete apparatus is described as follows:

To initiate operation of the refrigeration system, a heating medium such as steam is supplied through conduit 23 to header 22 where it is directed into one end of the upper row of inclined heating tubes 21 of the generator vessel 14. The steam flows through the upper row of tubes 21 and is then directed by the header 24 into the opposite end of the lower row of tubes 21 through which it flows to the header 25. Heat from the steam is transmitted through the tube sheets 14a underlying the headers 22, 24 and 25 and walls of the tubes 21 to heat the solution in the generator vessel 14 at a constant rate. Steam condensate flows through the inclined tubes 21 into the headers 24 and 25, respectively, and condensate in header 24 is delivered through pipe 26 to conduit 25 where it flows through the condensate drain 27.

Solution initially stands in the vapor liquid-lift conduit 15 at the same level as in the leveling vessel 54 and vapor expelled from solution in the generator 14 accumulates in the space e at the top of the generator vessel until it depresses the liquid level below the end of lift conduit 15 and escapes therethrough. When vapor commences to flow into the lower end of the lift conduit 15 the liquid in the conduit will tend to

be broken up and to flow down the sides of the lift tube by gravity until the conduit is cleared of liquid. The vapor will then flow through the conduit toward the separating chamber 16 in a continuous vapor phase. Due to the correlation of the area a of the lift conduit 15 with the rate of vapor generation in the generator 14 after the latter is operating at full capacity, the vapor will flow through the throat at a velocity sufficient to lift small droplets of liquid as it flows upwardly therethrough. It is believed that the violent agitation of the solution caused by rapid boiling creates a froth or foam in the space e at the top of the generator vessel which flows with the vapor toward the open end of the lift conduit. The flow of vapor into the end of the tube at high velocity tears the froth or foam into fragments which coalesce into small droplets. Vapor flowing past the droplets at high velocity imparts a frictional drag sufficient to overcome inertia and the force of gravity acting on the droplets to cause them to rise through the lift tube. After momentum has been initially imparted to the droplets the frictional drag need only slightly exceed the force of gravity acting on the droplets. By providing the upper or outlet end of conduit 15 with a cross-sectional area b and vapor velocity just sufficient to overcome the force of gravity on the droplets a minimum resistance to flow and pressure drop through the tube results. It is therefore apparent that the tapered lift conduit 15 reduces the pressure drop through the conduit to a minimum and reduces to a minimum the hydrostatic reaction head required to balance the lifting forces in the lift tube. With a minimum pressure drop in lift tube 15 and a minimum reaction head acting on the generator 14, the solution boils at a low pressure and temperature providing a maximum temperature differential between the solution and steam so that a minimum heating surface is required. The reaction head constitutes the difference in levels h and the difference in density of the solution in conduit 55 and in the generator 14 but the reduced reaction head permits a small difference in levels h and a decreased overall height of the apparatus.

Vapor entering the separating chamber 16 continues to flow upwardly through the baffles 29 and 30 and conduit 31 into the condenser 17 where it is condensed to a liquid. The liquid refrigerant flows through the restricting device 33 and conduit 32 into the uppermost tube 34 of the evaporator 18. Liquid refrigerant then flows through each tube 34 successively from the top to the bottom of the evaporator and evaporates at a low pressure and temperature corresponding to the vapor pressure of refrigerant in absorbent at the absorber temperature to cool air or other medium flowing over the exterior of the tubes and between the fins 38.

Absorption solution, weak in refrigerant, separated from vapor in the separating chamber 16, flows by gravity to the absorber 19 in the path of flow including the conduit 49, inner passages 50 of liquid heat exchanger 20, and conduit 51 to liquid distributor 41. The absorption solution is then distributed by the liquid distributor 41 for gravity flow over the relatively cool serpentine coils 48 to provide a large absorption surface. Due to the affinity of the absorption solution for refrigerant vapor the vaporized refrigerant from the evaporator tubes 34 flows through the headers 35 and 36 into the absorber 19 where it is absorbed in the absorption solution. Such

absorption of refrigerant vapor reduces the vapor pressure and temperature at which the refrigerant evaporates to produce the refrigerating effect. Absorption solution strong in refrigerant then flows by gravity from the absorber 19 back to the generator vessel 14 in the path of flow including the conduit 52, outer passages 53 of the liquid heat exchanger 20, leveling vessel 54 and conduit 55 to complete the cycle of operation.

During operation of the refrigeration system, non-condensable gases are continuously purged from the condenser 17 through the device 33 and from the absorber 19 through the purge device 56 which transfers them to the storage vessel 61. Liquid refrigerant overflowing from the evaporator 18 accumulates in the concentration chamber 62 to regulate the concentration of the absorption solution until an equilibrium is reached for the particular operating conditions. The amount of storage of liquid refrigerant in chamber 62 is controlled by the difference in pressure between the high and low pressure sides of the system.

Fig. 2 illustrates a vapor liquid-lift 70 of modified construction having a divergent passage 25 formed by flattening the opposite sides of a cylindrical tube. As shown in Figs. 3 and 4, the upper or outlet end 71 of the lift conduit 70 is circular while the lower or inlet end 72 of the tube is flattened to an oval shape and the cross-sectional area of the tube diverges from the bottom to the top thereof. It will be noted that the area *a* at the lower end 72 of the tube 70 provides a throat of such size as to produce the required vapor velocity and the area *b* at the 30 upper or outlet end 71 is of a larger size to produce a lesser vapor velocity. For any particular capacity a tube 70 will be selected having the cross-sectional area *b* desired and the tube is progressively flattened to provide a throat *a* of 40 a size correlated to the rate of vapor generation to produce the particular velocity required to lift liquid at the desired rate. Lift conduit 70 operates in the same way as lift conduit 15.

Fig. 5 illustrates a further modified construction of vapor liquid-lift conduit 75 which is heated throughout its length. Vapor liquid-lift conduit 75 has an upper portion 76, a throat *a*, and a lower converging portion 77. The upper portion 76 may diverge progressively from throat *a* to its upper end as illustrated in Figs. 1 and 2 but preferably the upper portion has a section 76a which diverges from the throat for about one third the height of the upper portion and a cylindrical section 76b above the diverging section. The intermediate divergent section 76a preferably has its sides flattened from the cylindrical cross-section *b*, see Fig. 6, to an oval cross-section *a* forming the throat. The lower portion 76 progressively converges from its closed bottom having a cross-sectional contour *c* to the throat *a*.

The conduit 75 is enclosed throughout its length by a jacket 78 providing a heating chamber 79 around the conduit. The end of conduit 55 from the leveling vessel 54 is connected to the portion 77 of lift conduit 75 adjacent its lower end and the jacket is provided with an inlet conduit 80 for a heating medium such as steam, a vent conduit 81 adjacent the upper end of the jacket and a condensate drain 82 at the bottom of the jacket. The construction illustrated in Fig. 5 provides a lift conduit 75 having a relatively large heat transfer surface while providing a throat *a* sufficiently small to produce the vapor velocity required. If for any particular installa-

tion it is found that the surface area of the lift conduit 75 is not sufficient to produce the heating required with a circular cross-sectional area *b*, the entire tube may be flattened to maintain the same cross-sectional area while providing an increased heat transfer surface. Thus, the construction illustrated in Fig. 5 adapts a single heated conduit to be used with an absorption refrigeration system in a large range of capacities to produce both the vapor velocity and heat transfer surface required. While the divergent lift conduit of the present invention is preferably used in a droplet type lift, it may be used on a climbing film type lift.

In operation, steam supplied to chamber 79 transfers heat through the wall of the lift conduit 75 to expel vapor from solution standing at the level *x*. The cross-sectional area *a* at the throat is correlated to the heat transfer surface of the lower portion 77 to cause vapor to flow through the throat at sufficient velocity to raise droplets of liquid at the desired rate. It has been found that a lift conduit having a divergent section 76a extending about one-third the height of the upper portion 76 operates equally as well as a conduit diverging throughout its length and is more easily manufactured in large sizes. The cross-sectional area *b* need only be of a size sufficient to overbalance the force of gravity acting on the liquid droplets at the outlet from divergent section 76a. The droplets are further heated in the upper cylindrical section 76b to expel additional vapor so that the passage may be even more divergent with additional heating surface than the previously described forms.

Fig. 9 illustrates a still further modified construction of vapor liquid-lift conduit 85 adapted for full length heating. The vapor liquid-lift conduit 85 comprises a cylindrical tube deformed by folding one side inwardly to arcuate shape to increase the heating surface without increasing the lateral dimensions of the conduit. It will be noted that the lift conduit 85 has an upper divergent portion 86 and a lower converging portion 87 with a throat *a* therebetween. Fig. 10 illustrates the outlet area *b*, Fig. 11 illustrates the throat portion *a* while Fig. 12 illustrates the area *c* at the lower end of the conduit. The lift conduit 85 is enclosed in a heating jacket 88 having a steam inlet 89 adjacent the bottom, a vent conduit 90 adjacent the top, and a condensate drain 91 at the bottom of the jacket. The conduit 55 for solution strong in refrigerant is connected to the lower converging portion of the vapor-lift conduit 85.

It will now be observed that the present invention provides an improved vapor liquid-lift for use in absorption refrigeration systems and having a restricting throat to produce a vapor velocity sufficient to lift liquid at the desired rate and a diverging cross-sectional area above the throat. It will also be observed that the present invention provides an improved vapor liquid-lift having a single conduit so constructed as to provide the necessary cross-sectional area and heating surface for any particular operating condition. It will still further be observed that the present invention provides an improved vapor liquid-lift which operates with a minimum pressure drop, a low solution temperature and a minimum heat transfer surface.

While several forms of the invention are herein illustrated and described, it will be understood that further modifications may be made in the construction and arrangement of elements with-

11

out departing from the spirit or scope of the present invention. Therefore without limitation in this respect, the invention is defined by the following claims.

I claim:

1. In an absorption refrigeration system, an absorption solution circuit having an upright lift conduit, the parts of said circuit being arranged for the gravity flow of absorption liquid to the bottom of said lift conduit, means for heating liquid in said circuit to expel refrigerant vapor, and at least a portion of said lift conduit having diverging walls to provide a passage of progressively increasing cross-sectional area. 10

2. In an absorption refrigeration system, an absorption solution circuit having an upright lift conduit, the parts of said circuit being arranged to maintain absorption liquid in said circuit at a level above the bottom of said lift conduit, means for heating the absorption solution in said conduit to expel vapor therefrom at a constant rate, and said lift conduit having a throat adjacent its lower end of a cross-sectional area correlated to the rate of vapor generation to cause vapor to flow therethrough at sufficient velocity to initiate upward movement of liquid and diverging walls above the throat. 25

3. In an absorption refrigeration system, an absorption solution circuit having an upright lift conduit, means to maintain absorption liquid in said circuit at a level above the base of the lift conduit, means for heating liquid in said circuit to expel refrigerant vapor, and said lift conduit having a throat of a cross-sectional area correlated to the rate of vapor generation to cause vapor to flow upwardly therethrough in continuous vapor phase at sufficient velocity to raise droplets of liquid and shaped to provide a divergent passage above the throat for lifting the liquid with a minimum pressure drop. 30

4. In an absorption refrigeration system, an absorption solution circuit comprising a generator vessel in which refrigerant vapor is expelled from solution by the application of heat, an absorber above the generator in which refrigerant vapor is absorbed into absorption solution, a separating chamber above the absorber, a vapor liquid-lift for lifting absorption solution from the generator to the separating chamber for gravity flow through the absorber back to the generator, means for heating said generator, and said vapor liquid-lift consisting of a single upright conduit connected between the generator and separating chamber and formed to provide at least a section of progressively increasing cross-sectional area. 45

5. An absorption refrigeration system in accordance with claim 1 in which the vapor liquid-lift conduit comprises a tube progressively tapered from the bottom to the top of the tube. 50

6. An absorption refrigeration system in accordance with claim 1 in which the vapor liquid-lift conduit comprises a cylindrical tube having

12

at least one side flattened progressively from one end toward the other to provide a gradually increasing cross-sectional area from the bottom to the top of the tube.

5 7. An absorption refrigeration system in accordance with claim 1 in which the heating means is in the form of a generator vessel and the vapor liquid-lift conduit is a tube formed to provide a divergent passageway upwardly from the generator vessel.

8. An absorption refrigeration system in accordance with claim 1 in which the vapor liquid-lift conduit comprises a tube formed to provide a converging lower portion and a diverging upper portion with a restricting throat between the portions.

9. An absorption refrigeration system in accordance with claim 1 in which the vapor liquid-lift conduit comprises a tube having a side flattened intermediate its ends to provide a converging lower portion and a diverging upper portion with a restricting throat therebetween, and the heating means comprises a chamber surrounding the conduit throughout its length.

10. An absorption refrigeration system in accordance with claim 1 in which the vapor liquid-lift conduit comprises a lower heat transfer section, a section above the heat transfer portion having divergent walls to provide a restricting throat therebetween, a section above the divergent section having the same cross-sectional area as the latter, and the heating means comprises a chamber surrounding the conduit throughout its length.

11. An absorption refrigeration system in accordance with claim 1 in which the vapor liquid-lift conduit comprises a tube progressively deformed from a cylindrical contour at one end to an arcuate contour at the opposite end to provide a passage therethrough of gradually increasing cross-sectional area.

12. An absorption refrigeration system in accordance with claim 1 in which the vapor liquid-lift conduit comprises a tube progressively deformed to arcuate shape intermediate its ends to provide a converging lower portion and a diverging upper portion with a restricting throat therebetween, and said heating means comprises a chamber enclosing the conduit throughout its length.
